US00D911403S

(12) **United States Design Patent** (10) **Patent No.:** **US D911,403 S**
(45) **Date of Patent:** **** Feb. 23, 2021**

(54) **CONTROLLING APPARATUS FOR
SOLDERING**

(71) Applicant: **Guangzhou Yihua Electronic
Equipment Co., Ltd.**, Guangdong (CN)

(72) Inventor: **Mingkang Gou**, Guangdong (CN)

(73) Assignee: **Guangzhou Yihua Electronic
Equipment Co., Ltd.**, Guangdong (CN)

(**) Term: **15 Years**

(21) Appl. No.: **29/691,135**

(22) Filed: **May 14, 2019**

(51) LOC (13) Cl. **15-09**

(52) U.S. Cl.

USPC **D15/144.2**

(57) **CLAIM**

The ornamental design for a controlling apparatus for soldering, as shown and described.

DESCRIPTION

FIG. 1 is a perspective view of the controlling apparatus for soldering;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines show portions of a controlling apparatus for soldering that form no part of the claimed design.
